US0D1063836S

(12) **United States Design Patent** (10) **Patent No.:** **US D1,063,836 S**
(45) **Date of Patent:** **** Feb. 25, 2025**

(54) **WIRELESS CHARGER**

(71) Applicant: **Yongwen Zeng**, Xingning (CN)

(72) Inventor: **Yongwen Zeng**, Xingning (CN)

(**) Term: **15 Years**

(21) Appl. No.: **29/894,509**

(22) Filed: **Jun. 9, 2023**

(51) LOC (15) Cl. **13-02**

(52) U.S. Cl.

USPC **D13/108**

CLAIM

The ornamental design for a wireless charger, as shown and described.

DESCRIPTION

FIG. 1 is a front perspective view of a wireless charger, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the wireless charger shown in a folded configuration.

The broken lines shown in the drawings illustrate portions of the wireless charger that form no part of the claimed design.

1 Claim, 8 Drawing Sheets
